(57) CLAIM

The ornamental design for a purse stand, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a perspective view of a first embodiment of a purse stand.

FIG. 2 is a top plan view thereof.

FIG. 3 is a bottom plan view thereof.

FIG. 4 is a front side elevation view thereof, the back side elevation view being a mirror image.

FIG. 5 is a right side elevation view thereof, the left side elevation view being a mirror image.

FIG. 6 is a perspective view of a second embodiment of a purse stand.

FIG. 7 is a top plan view thereof.

FIG. 8 is a bottom plan view thereof.

FIG. 9 is a front side elevation view thereof, the back side elevation view being a mirror image; and,

FIG. 10 is a right side elevation view thereof, the left side elevation view being a mirror image.

1 Claim, 4 Drawing Sheets
